AXMINSTER SPOOL WINDER

Conrad C. Blom, Longmeadow, Mass., assignor to
Bigelow-Sanford Carpet Co. Inc., Thompson-
ville, Conn., a corporation of Massachusetts

Application March 11, 1940, Serial No. 323,261

11 Claims. (Cl. 28—55.5)

This invention relates to apparatus for winding yarn and has for its object to provide novel mechanism for applying tension to the yarn during the winding.

The winding of pile yarn on spools used in Axminster weaving is particularly exacting with respect to the application of the proper amount of tension. The difficulty is due largely to the softness of the yarn and to a difference in tension between the overwinding and underwinding runs of the yarn which heretofore has resulted in differences in the hardness of the yarn on the several spools composing a pattern. The degree of hardness of the yarn controls the amount of retraction of the cut ends of the yarn upwardly into the tubes of the tube frame when the draw off tension in the yarn is released by the cut. A variation in the lengths of the tuft ends protruding from the tubes which thus results from variation in spool hardness produces either objectionable high and low rows or excessive waste if the variation is trimmed.

The object of my invention is to provide mechanism which uniformly tensions the yarn during the winding, whether overwinding or underwinding, and which thereby produces spools of uniform hardness. To that end I have provided a setting frame which preferably utilizes the torque in the driving mechanism in a novel way for applying at least a portion of the tensioning pressure of the winding rolls against the spool and which equalizes the pressure as between the several rolls, however applied.

In the drawings—

Fig. 1 is a side elevation view of a machine embodying my invention;

Fig. 2 is a vertical section taken on the line 2—2 of Fig. 1;

Fig. 3 is a diagram showing the positions of the rolls and the spool receiver during the winding operation, and

Fig. 4 is a detail vertical section on the line 4—4 of Fig. 2.

Referring first to Fig. 3, the yarn 2 to be wound on the spool 4 is drawn in the direction shown by the arrow from a creel or supply (not shown) through the usual tension rolls 6, reed 8 and over the guide roll 10 to the spool or receiver 4. The spool is peripherally engaged and rotated by three driving rolls 12, 14 and 16 preferably disposed at substantially equal intervals about the receiver. My apparatus is adapted both to underwind and to overwind a spool for which purpose the yarn is guided to the spool in the directions indicated respectively at 10A and 10B.

The roll 14 mounted on a shaft 20 has a fixed axis and is adapted to be power rotated in one direction or the other for underwinding or overwinding a spool, by mechanism to be referred to.

5 The substantially equidistant spacing of the rolls about the periphery of the receiver shown in full lines in Fig. 3 at the beginning of the winding is preferably preserved until the winding is completed so that throughout the winding operation the yarn on the spool is engaged at three substantially equidistant points at which tension is applied to the yarn. To permit divergence of the rolls as the spool fills, while preferably preserving the equidistant spacing, and also to aid in the application of pressure, the rolls 12 and 16 are preferably both mounted on movable axes. The roll 16 is mounted on a shaft 22, one end of which is carried by a crank arm 26 (see also Fig. 1) mounted to rotate about the axis of shaft 28 and the other end of which shaft 22 is mounted on a similar arm (not shown) rotating about the axis of the opposite end of shaft 28. By this means roll 16 is adapted to be swung gradually from its full line position to its dotted line position indicated at 16a, as the spool fills and thereby moves from its full line position to its dotted line position 4a.

20 In similar fashion roll 12 is mounted on shaft 24 carried at one end on a crank arm 32 mounted to rotate about the axis of shaft 34 and at the other end on a similar crank arm not shown rotating about the axis of shaft 34. Thus, as the receiver fills to its dotted line position indicated at 4a, the roll 12 is moved to its dotted line position 12a.

25 After the winding of the spool has been completed the roll 12, now in its position 12a, is swung back about the axis of shaft 34 to the position 12b for access to the wound spool 4a to remove the same and replace it with an empty spool in the position indicated at 4.

30 Tension on the yarn during winding is effected in part by differences in the speeds of the three winding rolls. In accordance with the preferred embodiment of my invention, when underwinding roll 16 is an idler, roll 14 is driven at a predetermined rate of speed and roll 12 is driven at a predetermined rate of speed that is faster than that of the roll 14. Conversely, for overwinding roll 12 is an idler, roll 14 is driven at a predetermined rate of speed and roll 16 is driven to rotate faster than roll 14. Thus, for either direction of wind the yarn is tensioned at three substantially equally spaced points about the periphery of the receiver.

Referring to Figs. 1 and 2, the machine has side frame members 50 and 52. Roll 12 is shown in Fig. 2 in a position intermediate its 12a and 12b positions (Fig. 3). The roll would not assume this position during winding, but it has been shown therein for clarity of illustration. In Fig. 1 it is shown abutting an empty receiver. The cranks 32 which, as stated above, support opposite ends of the shaft 24 carrying roll 12, are extended to form housings for the gears 68 and 70, to be described. The cranks have circular hubs 56 received in bearings in the side frame members 50 and 52. The hubs 56 are apertured to form bearings for the shaft 34 which protrudes outwardly beyond the frame members 50 and 52. Adjacent its opposite ends the shaft 34 carries loosely mounted on it the sprockets 58. The hub of each of the sprockets 58 is connected as by a stud 74 to the hub 56 of the crank arm 32 so that the sprockets 58 and the cranks 32 rotate together about the axis of shaft 34.

Mounted on the left hand end of shaft 34, as viewed in Fig. 2, is a sprocket 62 which at times rotates shaft 34 and, by means of gears 68 and 70, the former fixed to shaft 34 and the latter fixed to shaft 24, imparts rotation to roll 12. In order that the sprocket 62 may at times drive roll 12 in this manner and at other times may permit idle rotation of roll 12 independently of the rotation of sprocket 62, the sprocket is connected to the shaft 34 by means of a one-way clutch illustrated by a comparison of Figs. 2 and 4. Fixed to shaft 34 as by key 60 is the hub 51 of a cap 63. Journalled on the hub 51 is the hub 65 of sprocket 62. Fixed to the sprocket 62 is a disk 67 having tapered slots 69 in its periphery which receive the rollers 71. As sprocket 62 rotates counterclockwise, as viewed in Fig. 4, rollers 71 jam in tapered slots 69 so that rotation of disk 67 is imparted to cap 63 and thereby to shaft 34 to rotate roll 12 clockwise, as indicated by the arrow in Fig. 1.

As stated above, the roll 16 is mounted on a pair of cranks 26 at its opposite ends, one of which is indicated in Fig. 1. The cranks 26 are rotatably mounted on shaft 28. The hubs of the cranks 26 are provided with arms 82, for a purpose to be described, instead of sprockets corresponding to the sprockets 58 described with reference to roll 12. The roll 16 is power rotated from sprocket 80 by gears 86 and 84 of which the former is connected by a one-way clutch indicated in dotted lines to shaft 28 driven by sprocket 80 and the latter is fixed to shaft 22 which carries roll 16. The one-way clutch drives roll 16 counterclockwise and lets it idle clockwise.

The fixed roll 14 is secured to shaft 20 on one end of which is secured a driving sprocket 90.

Power for rotating the three rolls is derived from the shaft 92 connected by pinion 94 and gear 96 to shaft 98 on which is secured sprocket 100. A sprocket chain 102 passes in driving engagement with sprocket 100, with sprocket 98 fixed to the shaft 20 of roll 14, with sprocket 82 on the shaft 34 from which roll 12 is driven and with sprocket 80 on the shaft 28 from which roll 16 is driven. The power source is reversible to drive the rolls selectively in a direction to underwind a receiver, in which the chain and gears rotate in the directions shown by arrows in Fig. 1, or selectively in the overwind direction where the chain and gears rotate in directions opposite to those shown. In underwinding a spool, roll 16 idles because of the one-way clutch

above noted, roll 14 is power driven and roll 12 is driven to rotate faster than roll 20. For overwinding roll 12 idles because of its one-way clutch, roll 14 is power driven and roll 16 is driven to rotate faster than roll 20.

Each of the sprockets 58 which, as above described, are fixed to the hubs 56 of the cranks 32 on which roll 12 is mounted, is connected by a chain 110, one of which is shown in Fig. 1, to a corresponding sprocket 112 fixed to shaft 114 (see also Fig. 2). The chain passes around an idler sprocket 99 loose on shaft 20.

Loosely mounted on opposite ends of the shaft 114 are cranks 118 having hubs 120 journalled on the shaft. For a purpose to be described, it is desirable at times to connect sprockets 112 with crank hubs 120 so they rotate together and at other times to disconnect them. For this purpose I employ, on each side of the machine, a pin 130 passing through an aperture 132 in a hub 133 which is coaxial with shaft 114 and is journalled in the side frame member. The pin also passes through aligned apertures 134 and 136 in the sprocket 112 and hub 120 of crank 118. To urge the pins 130 yielding into locking position through the apertures 134 and 136, I provide a compression spring 140 secured between a collar 148 fixed to pin 130 and a collar 148 fixed to shaft 114. Retraction of the pin 130 from the recesses 134 and 136 is manually effected by means of a collar 150 slidably mounted on shaft 114 and connected by link 152 to one end of pin 130. The collar 150 is pinned to shaft 114 by a pin passing freely through elongated slot 160 in the shaft. When shaft 114 rotates, collar 150 rotates with it as do pin 130 and hub 133. Movement of collar 150 lengthwise of the shaft and to the right as viewed in Fig. 2 is effected by a handle 166 fixed on a stud shaft 164 to which is also fixed a fork 162 whose arms are secured at 156 to a ring 157 slidably received by a groove in collar 150. To operate the right hand pin 130, collar 150 is connected by link 170 to a rock arm pivoted at 174 to shaft 114 and connected by link 176 to the right hand pin 130.

The cranks 118 (Fig. 1) are connected by links 124 to the aforesaid cranks 82 fixed to the hubs of cranks 26 on which roll 16 is mounted.

For a purpose to be described, shaft 114 carries pinion 190 fixed to it and meshing with rack 192 carried by piston rod 194, the piston of which is received within the cylinder 196 and actuated pneumatically, hydraulically, or as desired.

In apparatus constructed as above described, I utilize the torque developed by the gears which drive the rolls for automatically applying pressure between the rolls and the spool. Thus, when unwinding a spool, the yarn is delivered in the position 10A (Fig. 3) and the power source 92 is rotated to effect clockwise drive of the rolls 14 and 12 at the speeds above indicated and to effect idle rotation of the roll 16 which initially engages the yarn as it passes to the receiver 4. The roll 12 being mounted on crank 32 can move toward or away from the receiver 4. The rotation of the gear 68 about the axis of shaft 34 not only drives roll 12 about its axis, but also creates a torque on the crank arm 32 tending to rotate the crank counterclockwise about shaft 34 as an axis and thereby pressing roll 12 against the spool. The amount of this torque pressure depends upon the resistance to rotation encountered by the roll 12. The softness of the yarn being wound on the spool 4 causes sufficient resistance to rotation of the roll 12 so that a considerable amount of

torque pressure of the roll against the spool is produced. As the spool gradually fills, forcing the roll 12 upwardly toward its 12a position (Fig. 3), a condition in which puffiness of the spool would occur in the conventional setting frame, the resistance to turning of the roll increases and thereby its pressure against the spool increases as is desired to eliminate such puffiness.

As the roll 12 is thus forced against the spool 4 by the torque derived from its driving mechanism, it also rotates sprockets 58 (Fig. 2) fixed to the hubs of cranks 32 on which roll 12 is mounted. By means of chains 110, sprockets 112 are rotated which, being connected by pins 130 to the hubs 120 of cranks 118, rotate those cranks. Links 124 thereby move downwardly as viewed in Fig. 1 to draw downwardly on cranks 82 fixed to the hubs carrying the cranks 26 in which the bearings for roll 16 are journaled. As a result of those connections, the torque in the mechanism driving roll 12 is effective not only to press roll 12 against the spool, but also to force roll 16 against the spool with an equal amount of pressure.

After the spool has been wound in an underwinding direction, top roll 12 is moved from its 12a to its 12b position for removal of the full spool and replacement by an empty one. For that purpose hubs 120 and sprockets 112 are first disconnected from each other by retracting their locking pins 130 and this is effected as above described by manipulating the lever 166. Thereafter the motivating fluid is admitted to cylinder 196 to move rack 192 upwardly and rotate shaft 114 clockwise as viewed in Fig. 1. This is effective to displace the roll 12 to its 12b position. It is automatically stopped when its extreme 12b position is reached.

A fresh spool is then inserted and after the yarn has been wrapped about it manually, the roll 12 is brought back to its full line position of Fig. 3 to commence the next winding operation. This is effected in an obvious manner by lowering the piston in cylinder 196. Thereafter sprockets 112 and hubs 120 are again locked together by re-insertion of pins 130 in their aligned apertures through elevation of hand lever 166. To aid in aligning these apertures, I provide a pin 231 (Fig. 1) against which crank 118 comes to rest when rolls 12 and 16 are in their proper positions for starting the winding.

To overwind a spool the yarn is introduced in its dotted line 10B position of Fig. 3 and the power shaft 92 is rotated in a counterclockwise direction to move the chain 102 and the sprockets with which it is connected in the directions contrary to those shown by the arrows. In this direction of drive roll 14 is driven counter-clockwise, desirably at the same peripheral speed that it was driven clockwise for underwinding, roll 12 is an idler and roll 16 is driven counter-clockwise at a peripheral speed greater than that of the roll 14 and preferably at the speed that roll 12 was driven for underwinding.

In this overwinding direction the resistance to rotation of the power driven roll 16 creates a pressure-applying torque which presses roll 16 against the spool 4 in the manner above described for roll 12 when underwinding. This pressure is transmitted through crank 82, links 124, sprockets 112 and chains 110 to sprockets 58 to urge the latter and the roll 12 in a counter-clockwise direction about the axis of shaft 34 to press roll 12 against the spool in the same amount as the roll 16 is pressed.

It is thus apparent that in a machine constructed in accordance with the preferred embodiment of my invention the two movable axis rolls are yieldingly pressed against the spool in an equal amount which is determined partly by the work involved in driving the last roll which the yarn engages as the spool rotates. The amount of torque is governed largely by the difference in speeds between the last driven roll 10 and the intermediate roll 14 and can be varied by varying the difference in speeds between these rolls. This can be effected in an obvious manner by replaceable sprockets or change gears. The amount of pressure is substantially the same for both of the movable axis rolls and it may be obtained without the use of springs, weights or other mechanism employed in the past for the purpose which add to the costliness and cumbersomeness of the machine.

My invention is not to be limited to the preferred embodiment above described which can be variously modified within the scope of the appended claims. Thus, the same torque effect can be obtained by the use of a chain drive instead of the gear trains herein described. For removing the roll 12 to its 12b position for removal of a full spool a hand crank attached to shaft 114 can be employed, but if a piston is used provision should be made, in an obvious manner, for escape of the motivating fluid during such rotation of shaft 114 as occurs when pins 130 are in locking position and rolls 12 and 16 are running. Although I have described the machine as deriving the pressure entirely from the torque of the driving mechanism, this can be supplemented or otherwise modified by the use of auxiliary pressure applying or opposing apparatus of conventional character. In the mechanism illustrated I could effectively employ cylinder 196 and its connections to shaft 114 as such auxiliary means. Whatever modification is used, my invention assures that the pressure is equally applied by both of the movable axis rolls and is the same for overwinding and underwinding.

I claim:

1. In a machine for winding yarn on a receiver, apparatus for rotating the receiver to wind yarn thereon including a roll disposed in peripheral engagement with the receiver, a crank on which said roll is mounted adapted to permit movement of the axis of the roll away from the axis of the receiver during the winding, a drive for rotating said roll including a rotating driver mounted on a shaft that is substantially parallel with but out of axial alignment with the roll, and means to drive the roll from said driver when the driver rotates in a direction to press the crank and roll toward the receiver and to effect idle rotation of the roll when the driver rotates in the reverse direction.

2. In a machine for winding yarn on a receiver, a pair of rolls adapted to rotate the receiver by peripheral contact therewith to wind yarn thereon, a pivoted crank for each of said rolls adapted to permit movement of the axis of its roll toward and away from the axis of the receiver, a rotating driver for each of said rolls mounted on a shaft that is substantially parallel with the axis of its roll and in proximity to the pivot for its crank, a connection between each roll and its driver so that one roll is driven clockwise and the other counterclockwise by its driver when the driver rotates in a direction to create a torque which presses the crank toward the receiver and so that each roll idles when its driver

rotates in the reverse direction, and a connection between said cranks by which torque pressure of either crank toward the receiver when its roll is being driven effects a substantially equal pressure of the other crank toward the receiver when its roll idles.

3. The device as defined in claim 2 in which each of the drivers is mounted co-axially of the pivot for the crank carrying the roll which it drives.

4. The device as defined in claim 2 which includes a reversible power source connected to both of said drivers.

5. In a machine for winding yarn on a receiver, the combination of three winding rolls adapted, by peripheral engagement with the receiver, to rotate the receiver selectively in an overwinding or underwinding direction, the first and last rolls engaged by the yarn as it passes to the receiver in either the overwinding or underwinding direction being mounted on pivoted cranks to permit movement of those rolls toward and away from the periphery of the receiver, driving means for each of said crank mounted rolls effective to drive the last roll engaged by the yarn as it passes around the receiver in either the overwinding or underwinding direction and effective to permit idle rotation of the first roll engaged by the yarn in either direction of rotation, said driving means for each crank mounted roll being adapted to rotate in a direction to create a torque which presses the roll when driven against the periphery of the receiver, and a connection between said cranks to effect pressure of the idle roll against the receiver.

6. A machine for winding yarn on a receiver including three rolls disposed successively around and in peripheral engagement with the receiver to wind yarn thereon, a crank on which one of said rolls is mounted, a pivot for the crank adapted to permit movement of the axis of the roll toward and away from the axis of the receiver, a drive for rotating said roll including a rotating driver mounted on a shaft having an axis spaced from and substantially parallel to the axis of said roll and in alignment with said pivot, a driving connection between the driver and the roll to drive the roll with the driver rotating in a direction to urge the crank and roll toward the receiver, at least one other of said rolls being power driven and there being a predetermined difference in peripheral speed between two successive power driven rolls which induces an effort by said driver sufficient to create a torque pressing the roll carried by the crank against the receiver.

7. The device as defined in claim 2 in which each of said drivers is mounted in proximity to the pivot for the crank carrying the roll which it drives.

8. A machine for winding yarn on a receiver including three rolls disposed successively around and in peripheral engagement with the receiver to wind yarn thereon, a crank on which one of said rolls is mounted, a pivot for the crank adapted to permit movement of the axis of the roll toward and away from the axis of the receiver, a drive for rotating said roll including a rotating driver mounted on a shaft having an axis spaced from the axis of said roll and in alignment with said pivot, a driving connection between the driver and the roll to drive the roll with the driver rotating in a direction to urge the crank and roll toward the receiver, the roll next preceding said crank mounted roll being driven

at a predetermined peripheral speed which is less than that at which said crank mounted roll is driven to induce an effort by said driver sufficient to create a torque which presses the roll, carried by the crank, against the receiver.

9. A machine for winding yarn on a receiver including three rolls, disposed successively around and in peripheral engagement with the receiver, two of said rolls being driving rolls to wind yarn

10 on said receiver, a crank on which one of said driving rolls is mounted adapted to permit movement of the axis of the roll away from the axis of the receiver during the winding, a drive for rotating said roll including a rotating driver mounted on a shaft spaced from and substantially parallel to the axis of said driving roll, a driving connection between the driver and the roll to drive the roll in one direction, a pivot for said crank so located that when the driver drives the roll in said one direction the driver creates a torque on said crank to press the crank and roll toward the receiver, and means in said connection operative when the driver rotates in the reverse direction to effect idle rotation of said roll.

15 10. A machine for winding yarn on a receiver including three rolls disposed successively around and in peripheral engagement with the receiver to wind yarn thereon selectively in an overwinding or an underwinding direction, the first and

20 third of which rolls are mounted on pivoted cranks permitting movement of those rolls toward and away from the periphery of the receiver, driving means for the first roll including a rotating driver mounted on a shaft having an axis substantially in alignment with the pivot

25 for its crank and a driving connection between the driver and said roll which drives the roll in a direction to underwind the receiver while simultaneously effecting rotation of the crank to

30 press the roll against the receiver and which permits idle rotation of said roll when the receiver rotates in an overwinding direction, driving means for said third roll including a rotating

35 driver mounted on a shaft having an axis substantially in alignment with the pivot for its crank and a driving connection between the driver and said third roll which drives said roll in a direction contrary to that in which said first

40 roll is driven to overwind the receiver while simultaneously effecting rotation of the crank to press the third roll against the receiver and which permits idle rotation of said third roll when the receiver rotates in an underwinding direction, and a connection between said cranks

45 by which said rotation of the crank for the first roll when said first roll is driven urges the third roll against the receiver when the third roll idles and rotation of the crank for the third roll when

50 said third roll is driven urges the first roll against the receiver when the first roll idles.

11. A machine for winding yarn on a receiver including three rolls disposed successively around and in peripheral engagement with the receiver

55 to wind yarn thereon selectively in an overwinding or an underwinding direction, the first and third of which rolls are mounted on pivoted cranks permitting movement of those rolls toward and away from the periphery of the receiver, driving means for the first roll including

60 a rotating driver mounted on a shaft having an axis substantially in alignment with the pivot for its crank and a driving connection between the driver and said roll which drives the roll in a direction to underwind the receiver while si-

65 70 75

multaneously effecting rotation of the crank to press the roll against the receiver and which permits idle rotation of said roll when the receiver rotates in an overwinding direction, driving means for said third roll including a rotating driver mounted on a shaft having an axis substantially in alignment with the pivot for its crank and a driving connection between the driver and said third roll which drives said roll in a direction contrary to that in which said first roll is driven to overwind the receiver while simultaneously effecting rotation of the crank to press the third roll against the receiver and which permits idle rotation of said third roll when the receiver rotates in an underwinding direction, 10 means to drive said second roll selectively in an overwinding or an underwinding direction at a

surface speed which is slower than the surface speed at which said first roll is driven in an underwinding direction and slower than the surface speed at which said third roll is driven in an overwinding direction to create an effort in the driving connections to said first and third rolls when driven which enhances the pressure-applying rotation of said cranks, and a connection between said cranks by which said rotation of the crank for the first roll when said first roll is driven urges the third roll against the receiver when the third roll idles and rotation of the crank for the third roll when said third roll is driven urges the first roll against the receiver when the first roll idles.

CONRAD C. BLOM.
